HANGER FOR DECORATIVE SCREEN ELEMENT

Joseph D. Sohn, 712 Fernwood, Apt. 7,
West Covina, Calif. 91790

Filed July 8, 1966, Ser. No. 3,000

Term of patent 14 years

(Cl. D21—1)

FIG. - 2

FIG. - 1

FIG. - 3

FIG. - 4

FIG. - 5

FIG. - 6

FIG. - 7

FIG. - 8

FIG. 1 is a front elevational view of a hanger for decorative screen element showing my new design;

FIG. 2 is a side elevational view thereof;

FIG. 3 is a bottom plan view thereof;

FIG. 4 is a perspective view thereof;

FIG. 5 is a front elevational view of a modified form of the hanger for decorative screen element shown in FIG. 1, wherein the holder portion has a substantially elliptical configuration;

FIG. 6 is a perspective view of a second modified form of the hanger for decorative screen element shown in FIG. 1, wherein the holder portion has a substantially diamond-shaped configuration;

FIG. 7 is a perspective view of a third modified form of the hanger for decorative screen element shown in FIG. 1, wherein the holder portion has a substantially rectangular configuration; and

FIG. 8 is a perspective view of a fourth modified form of the hanger for decorative screen element shown in

FIG. 1, wherein the holder portion has a substantially triangular configuration.

I claim:

The ornamental design for a hanger for decorative screen element, as shown and described.
